RADIATION METER

John E. Wagenseller, Secane, Pa.

Application December 15, 1953, Serial No. 28,081

Term of patent 14 years

(Cl. D52—1)

FIG. 1

FIG. 2

Fig. 1 is a perspective view of a radiation meter, showing my new design; and

Fig. 2 is a rear elevational view thereof.

I claim:

The ornamental design for a radiation meter, substantially as shown.
